UNITED STATES PATENT OFFICE.

OLUF C. JENSEN, OF NEW YORK, N. Y.

AUTOMOBILE-HORN.

1,318,673.

Specification of Letters Patent. Patented Oct. 14, 1919.

Application filed February 11, 1916. Serial No. 77,583.

To all whom it may concern:

Be it known that I, OLUF C. JENSEN, a citizen of the United States, residing at New York, in the county of New York and 5 State of New York, have invented certain new and useful Improvements in Automobile-Horns, of which the following is a specification.

My invention relates to signaling devices 10 such as are used on automobiles and other fast-moving vehicles and has reference particularly to hand-operated devices of this character.

These hand-operated devices, as heretofore constructed, have been more or less 15 awkward or unhandy and hard to operate, and one of the objects of this invention is to eliminate this unhandiness of operation and to render such devices operable by a 20 single, natural and easy movement of the hand.

Other objects are to lessen the number of 25 working parts and to provide a thoroughly practical simply constructed device which can be produced at a low cost.

These objects I have accomplished by 30 mounting the impact wheel of the device on an axis inclined downwardly and forwardly with respect to the sound-producing dia- 35 phragm and by operating said wheel by a rack geared to said wheel and mounted to slide on a downward and forward incline substantially parallel to the axis of said impact wheel. The drive gearing is prefer- 40 ably arranged to operate on the down stroke of the rack, thus making the device operable by a downward, forward thrust of the hand, a natural movement and one in which considerable force can be applied with but 45 slight exertion on the part of the operator.

Other features and details of structure 50 will appear as the specification proceeds, attention being directed to the accompanying drawing, forming a part hereof and wherein 55 I have illustrated the invention embodied in a practical and preferred form.

In the drawing, Figure 1 is a vertical sectional view taken through the casing of the 55 horn and showing the impact wheel and other parts in elevation; Fig. 2 is a detail view of the gear and rack, as seen from the rear; Fig. 3 is a sectional view taken substantially on the plane of the line 3-3 of Fig. 1, looking down on top of the impact wheel.

Considering the drawing now more in detail, 5 designates a sound-producing dia- 60 phragm suitably supported in a casing 6 and vibrated, in the construction illustrated, by the direct engagement of the roughened rim portion 7, of an impact wheel 8 there- with.

This impact wheel is shown journaled on an axis 10, set on a downward and forward incline convergent with respect to the plane 65 of the diaphragm, and the rim of the wheel is shown beveled in substantial parallelism with the plane of the diaphragm. The impact elements or protuberances on the rim of the wheel are shown engaging with a 70 contact element or button 11 at the center of the diaphragm.

A spindle 12, serves in the illustration, as a pivotal support for the impact wheel, the wheel being rotatably engaged on the lower 75 end portion of the spindle, and the spindle being supported in its inclined position by a step bearing 13 at the bottom and a bearing 14 at the top. The impact wheel is made relatively heavy to give it a flywheel 80 effect and it may, as indicated, rest upon and be supported by the step bearing 13, this bearing then serving in the double capacity as a thrust bearing for both the spindle and the impact wheel. 85

15 designates the actuating member, in the form of a slide-rack, rectangular in cross- 90 section, mounted to reciprocate, in a guide- way 16, also rectangular in cross-section, said slide being disposed substantially parallel to the axis of the impact wheel and pro- 95 vided on its side adjacent the spindle, with teeth 17, inclined to match the teeth of a spiral gear 18 fast on the upper end of the spindle, which gear 18 extends through a 95 suitable opening in the side of member 16 to engage teeth 17. The upper end portion of the slide projects upwardly, and rearwardly through the casing and is provided with a 100 suitable handle 19.

In the form of the invention illustrated, the impact wheel is operated only on the downward thrust of the slide or rack, this result being attained by interposing a one- 105 way driving connection at a point between the rack and the wheel, this connection being shown as a ratchet 20 on the spindle en- gaging a spring-pressed pawl 21 mounted on the upper face of the wheel, the teeth of the ratchet being faced to drive the pawl only 110

when the spindle is rotated on the down thrust of the rack.

A suitable spring 22 is usually provided for returning the rack to the uppermost, 5 extended position indicated in Fig. 1, and a stop-pin 24 on slide-rack 15, engages with the upper end of a slot 25 in member 16, to prevent the outward movement of the slide beyond the position shown in Fig. 1, that is, 10 out of operative engagement with gear member 18.

A sound-amplifying device, such as the horn 23, is usually provided, the same being made more or less ornamental in form, as 15 may be desired.

Signal device of this character are usually mounted in a position forward of and below the arm of the operator, from which the convenience and ease of operation of my invention will be the more readily apparent, it being seen that a natural downward and forward thrust of the hand serves to operate the device, this movement involving a straightening of the arm, in which considerable 20 force can be exerted with the expenditure of but little energy. In addition to the advantages as to ease and facility of operation, it will be seen that the invention consists of but few, inexpensive parts, simple 25 in design and not liable to get out of order.

I prefer that the impact wheel 8 shall be a shell of steel or other metal, with the teeth 7 formed therein as by drawing or stamping, with a core of heavy and cheaper metal 30 set in to give the necessary weight.

It will be apparent to those skilled in the art that various changes and modifications may be made without departing from the true spirit and scope of the invention, and 40 I would have it understood that the terms employed herein are used in a descriptive rather than in a limiting sense, except as

may be required by the state of the prior art.

I claim:

1. In a device of the character set forth, 45 the combination of a diaphragm, an impact wheel journaled on an axis disposed in convergent relation to the plane of said diaphragm, coöperating means on the rim of said wheel and said diaphragm for vibrating the diaphragm, an operating slide mounted to reciprocate in a guideway in a plane substantially parallel to the axis of said impact wheel and drive gearing between 50 said operating slide and said impact wheel. 55

2. In a device of the character set forth, 60 the combination of a diaphragm, a spindle journaled to rotate on an axis disposed in convergent relation to the plane of the dia- 65 phragm, an impact wheel rotatably supported on said spindle, a spiral gear on said spindle, a rack mounted to slide in a plane substantially parallel to the axis of said spindle and provided with teeth inclined to match the spiral gear on the spindle and coöperating means on the rim of the impact wheel and said diaphragm for vibrating 70 said diaphragm.

3. In a device of the character set forth, 75 the combination of a diaphragm, a rotatably supported impact wheel in rear of said dia- 80 phragm journaled on an axis inclined downwardly and forwardly toward the dia- phragm, a spiral gear carried by said wheel and an operating rack slidably mounted on a downward and forward incline substantially parallel to the axis of said impact wheel and provided with inclined teeth matching the teeth of the spiral gear of the impact wheel.

In testimony whereof I affix my signature.

OLUF C. JENSEN.
